UNITED STATES PATENT OFFICE.

JAMES H. CAPLAN, OF BOSTON, MASSACHUSETTS.

BUFFING COVER FOR ROTARY BRUSHES.

1,413,574.

Specification of Letters Patent. Patented Apr. 25, 1922.

Application filed February 14, 1919. Serial No. 277,089.

To all whom it may concern:

Be it known that I, JAMES H. CAPLAN, a citizen of the United States, residing at Boston, in the county of Suffolk and State of Massachusetts, have invented a new and useful Improvement in Buffing Covers for Rotary Brushes, of which the following is a specification.

The object of the invention is to provide 10 a more durable and efficient rotary brush cover used for buffing purposes and a simple and inexpensive method of making up the same.

In order to illustrate my invention I have 15 shown in the accompanying drawing a single embodiment thereof, wherein:—

Fig. 1 is a perspective view of a cover of 20 my invention shown applied to an ordinary rotary buffing brush of the broom straw type.

Fig. 2 shows the cover set as shown in Fig. 1 but with the cover removed.

Fig. 3 is a sectional view taken on line 3—3 on Fig. 1, but shows the brush in elevation and not in section.

Fig. 4 is an enlarged perspective view of the cover.

Fig. 5 shows the development of the circular cover as laid out diagonally on the 30 fabric from which the same is made, so that the texture of the finished cover comes on the bias and not on the straight weave of the fabric.

Fig. 6 shows a diagrammatic view of a 35 buffer-cover in action with a shoe being treated thereby.

The terms employed herein are used in the generic and descriptive sense to designate parts or elements, and are therefore not intended primarily as terms of limitation.

In the drawing, the numeral 10 represents 40 a closed, circular brush cover member of my design which is cut from the fabric or material "m" (preferably known as drill fabric) diagonally across the run of the same, as shown by the strip "B" in Fig. 5, for the purpose of eliminating the straight weave of the fabric running circumferentially around the finished brush cover, as is invariably the case with the usual brush covers in use today for buffing purposes.

11 represents the cover joint which is made diagonal, as shown in Fig. 4, where the free ends 12 and 13 of the cover (which 55 are cut diagonal and parallel) are permanently joined, as shown by the stitching "S"

or by any other suitable manner, for affecting an endless belt feature to yield the closed and circular effect required for the cover. The side edges 14 and 15 are each folded back and secured to the cover, as by the stitching 16, to form drawstring grooves or channels around the same which are open at the joint as "O" through which the drawstrings, cords or tapes "D" may be drawn 60 and protrude for the purpose of securing the cover in operating position with the brush, as shown in Fig. 1. 17 represents an ordinary rotary buffing brush which is used more particularly in the shoe manufacturing business; 18 represents the brush bristles which are usually of the broom straw type set radially in the brush, as shown in Fig. 1.

Having thus described the method of making and the details of my invention, the 75 manner in which the same may be employed is as follows:—

The drawstrings "D" are loosened and freed so that the sides of the cover may be full open, as shown dotted in Fig. 3, whereupon the same may be slipped over the bristles of the brush 17 into the position there shown dotted, then the overlapping sides may be folded over the brush by the tightening up on the drawstrings which effects a 80 gathering feature to the sides of the cover, as shown in Figs. 1, 2 and 3, then with the drawstrings properly tied up to keep the cover in such position the same becomes 85 ready for working operation, it being understood that a cover so fitted and secured to the brush with which the same is associated will be caused to rotate with the brush and may then serve as a buffing wheel.

While buffing covers have been used heretofore in the shoe making business, yet it is a fact that the same have always been cut the straight way of the fabric and not on the bias, as is true of my invention; and further, where closed covers (meaning unit 100 endless covers) were used, the same were not only cut on the straight weave of the fabric but the joint was made straight across and parallel with the axis of the wheel and not oblique and diagonal to it as my invention 105 calls for.

By making the cover with the weave and joint thereof on the bias, as explained, rather than on the straight of the fabric, the life of the cover is greatly increased 110 since the resistance upon it is greatly decreased, for the friction and wear of the ob-

ject being treated thereagainst is no longer localized, as is the case with the straight cut and straight jointed cover, but is distributed obliquely across the same, as indicated by the small arrows in Fig. 6. The oblique positions of the warp and filling threads of the fabric serve to reinforce the working section of the cover against the strain encountered thereby.

10 It must be understood that the oblique positions of the warp and filling threads of the fabric serve as better binders for the bristles of the brush than can be had with the filler threads positioned parallel with the brush axis, and that the oblique positions of the threads of the fabric allow for a greater supporting feature thereto over a longer length of brush than is otherwise attainable. Therefore, the cover becomes better qualified to resist the work and friction against it and becomes more durable and lasting.

Having thus described my invention in detail, what I claim as new is:—

25 1. A circular buffer brush cover comprising a strip of fabric cut on the bias with the ends thereof cut parallel to each other but

diagonally disposed to the sides of said strip and permanently secured together to form a diagonal joint for the cover, and the 30 sides thereof folded and secured to the cover to form drawstring channels; and drawstrings provided in said channels for securing the cover in working position with the buffer brush.

2. A closed circular buffer brush cover comprising a strip of suitable fabric cut on the bias having parallel ends diagonally disposed to the sides of said strip and permanently secured together to form a complete 40 circular band of said strip, drawstring retaining means provided on the sides of said brush cover and provided with drawstring outlets at the joint section of said cover, and drawstrings adapted to gather the sides of 45 the cover for securing the same to the buffer brush.

In testimony whereof, I hereunto set my hand this twelfth day of February, 1919.

JAMES H. CAPLAN.
